UNITED STATES PATENT OFFICE.

ARTHUR H. T. WILLIAMS, OF PORTLAND, OREGON.

GAS HOLDER.

Application filed July 12, 1926. Serial No. 121,801.

This invention relates generally to gas holders, and particularly to a special form of holder in which a plurality of high-pressure holders are held within the usual water space of a low-pressure holder.

The first object of this invention is to provide a gas holder whose holding capacity for a given outside dimension is much greater than that of the ordinary low-pressure holder now in common use.

The second object is to reduce the dangers and losses caused by leakage from high-pressure holders by collecting any gas which may escape therefrom within the low-pressure holder from which gas is delivered to the consumer.

The third object is to reduce the loss of time and power ordinarily consumed in stepping pressures up and down for the purpose of delivering it to distant points and for distributing it through the consumers' mains.

The fourth object is to construct a gas holder in which the maximum amount of gas can be held with the expenditure of only a relatively small amount of labor, and with the requirement of the least possible amount of steel and other materials in its construction consistent with safety.

The fifth object is to construct a holder having such parts ordinarily subject to inspection, made easily accessible therefor.

The sixth object is to construct a holder that certain of its units can be emptied and scoured to admit workmen, while other units can carry gas at full pressure thereby avoiding a shutdown of a holder whenever it is desired to make an inspection.

The seventh object is to construct submerged high-pressure gas holder units in a manner to overcome their natural buoyancy by providing special forms of anti-buoyancy rings.

The eighth object is to make it possible to deliver either high or low-pressure gas from a holder, separately or at the same time.

The ninth object is to construct a holder of large capacity without subjecting its foundation to enormous loads of water. This is often of considerable importance where holders must be placed on made land or on ground affording a poor footing for a foundation. This applies to new holders. Where the capacity of old holders is to be increased the weight on the foundation is actually reduced.

The tenth object is to make this arrangement readily applicable to new or existing gas holders, thereby making it possible to increase the capacity of a holder without requiring the use of more ground space.

These and other objects, will become more apparent from the specification following as illustrated in the accompanying drawings, in which:

Figure 1 is a vertical section through a gas holder equipped with a plurality of high-pressure units installed in an existing holder. Figure 2 is a plan of Figure 1. Figure 3 is a vertical section of a modified form of holder also employing existing foundations. Figure 4 is a horizontal section taken along the broken line 4-4 in Figure 3. Figure 5 is a vertical section through the lower portion of a holder showing the high-pressure units installed on a foundation especially designed for the purpose. Figure 6 is an enlarged section through an anti-buoyancy ring showing its position between a high-pressure shell and an existing foundation. Figure 7 is a diagrammatic plan of another form of high-pressure unit arrangement. Figure 8 is a side elevation of one of the units shown in Figure 7. Figure 9 is a diagrammatic plan of still another plan of high-pressure unit arrangement. Figure 10 is a side elevation of a pair of units shown in Figure 9.

Similar numbers of reference refer to the same parts throughout the several views.

Referring in detail to the drawings, I have illustrated in Figures 1 and 2 the usual form of gas holder, including the foundation 11 on which is mounted the holder consisting of the tank 12 and bells or lifts 13 and 14 which are held in correct relation by the guide frames 15. Structural details have been omitted for the purpose of simplifying the drawings. Riveted or welded joints may be used as seems best.

Inside of the lifts are placed a plurality of high-pressure units 16 which, in this instance, are in the form of spherical shells so arranged within the holder as to permit the introduction of the maximum number of units, at the same time keeping the units accessible for inspection. In this arrangement the central unit 16 is connected to each of the outer units by a large pipe 17 through which a man can pass. Each pipe 17 is provided with a manhole cover 18.

It is evident that each unit 16 which is submerged in the water 19 of the holder would, owing to its natural buoyancy, exert a tremendous lifting action on the foundation if merely attached thereto. To overcome this condition there are provided anti-buoyancy rings 20 which may be attached to the units 16 by means of the ring 21, as shown in Figure 6, and the ring 20, in turn, is attached to the floor plate 22 by means of a second flanged ring 23. A suitable plastic composition 24 is placed between the members 20, 22, and 23. In some cases the ring 20 can be dispensed with by making 15 the ring 21 a plain vertical wall whose lower end can be attached to the floor plate 22.

Ports 25 connect the ring 20 with its spherical unit 16. Each unit 16 is connected by means of a pipe 26 to the manifold 27 which is provided with four valves 28, 29, 30 and 31. A branch 26^A which is a high-pressure discharge main, also leads from the pipes 26 and is provided with a valve 26^B. The valve 28 is between the pipe 26 and the manifold 27 and controls the flow of gas to or from the spheres 16.

Low-pressure gas is taken from or admitted to the holder through the pipe 32 which connects with the manifold 27 through the valve 29. Gas from the source of supply enters the manifold 27 through the valve 30. The valve 31 controls the flow of gas from the manifold 27 to the main 33.

Water must be kept out of the spaces 35 under the spheres 16 within the rings 20 and drain pipes 34 are provided to lead any leakage into the gutter 35. A tunnel 36 is also provided to give access to the central sphere 16 and for the operation of the various valves 37 in the pipes 26 which lead to the rings 20.

In the form shown in Figure 5, which illustrates a foundation designed for use with spherical units 16, a seat or depression 45 is formed in the foundation 38 for each sphere 16, and each depression is provided with a drain pit 39 which prevents any pressure from being built up under the sphere, which pressure would otherwise tend to lift 50 the sphere.

In the modification illustrated in Figures 3 and 4, toroidal shell 40 is employed with the central shell 16^A by means of which access is gained to the outer shell 40 through the pipes 17^A. In this case the anti-buoyancy ring 20^A is smaller than the shell 40 and the rings 21^A and flange 23^A are proportionate in size. Frames 41 support the shell 40 and frames 42 support the shell 60 16^A.

An arched cover 43 spans the space between the members 40 and 16^A and prevents water from getting under the high-pressure units. Although not illustrated in Figure 65 3, it is evident that the space from which

water is excluded must be open to the atmosphere and drained.

No crown support for the low-pressure holder is indicated, but it can be seen that it will be as easy to support the crown from 70 the tops of the high-pressure containers, as it is on the foundation itself.

In Figure 7 the high-pressure unit 44 takes the form of a clover leaf, thereby occupying the maximum amount of the water 75 area of the holder compared with the other forms indicated. The respective lobes 45 of each unit may be cylindrical in nature with hemispherical ends, or the end may be merely bulged. Stay-plates 46 are employed 80 within the unit 44 to withstand the pressures to which the shell may be subjected. The structure of the unit 44 is only suggested herein but will be found fully explained in my co-pending application, Serial Number 85 122,580.

In Figures 9 and 10 still another form of high-pressure container 16^B is indicated. In this form, the outer shells 16^B are somewhat cylindrical with rounded ends, while 90 the central unit 47 is spherical, and is employed as a gateway to the outer shells. It is easy to see that the units 16^B can also be turned to a vertical position, which makes them appear in plan as in Figure 2. In 95 this case the shell 47 could be similar to the shells 16^B.

The object in illustrating the various forms as shown is only to show that many different shapes and numbers of high-pressure units can be employed, rather than to advance any one form as best suited to all purposes. The particular type selected should be controlled by certain factors always present in the selection or designing 100 of any type of gas holder.

In the past few years there has been a marked tendency to get away from the old style low-pressure holders as it has become a recognized fact that these holders carry 110 only a relatively small amount of gas when compared with the cost of ground, maintenance and other items. Certain operators are going into the use of elevated spheres and employing same as high-pressure holders, and others have resorted to the piston type of holders employing a tar seal for the piston.

While it is very desirable to store gas at 120 higher pressures than are employed by the average consumer, the objection to doing so in the past has arisen from the fact that gas is extremely difficult to hold in metal containers at a high pressure when such containers are subjected to ordinary changes 125 in temperature. It is a well known fact that the annual loss of gas from high-pressure containers is enormous.

In this instance however, any gas which 130 may escape from the high-pressure container

will be caught by the low-pressure container and delivered to the consumer in the usual way instead of escaping into the atmosphere as a loss and a fire hazard.

5 Again, the high-pressure containers are submerged in water and will naturally have a very even and a low temperature, when compared with the out of door high-pressure container whose structure naturally 10 undergoes many and severe stresses during temperature changes, with the result that the seams are opened and gas escapes to the atmosphere.

15 By maintaining low temperatures within the high-pressure containers, correspondingly larger volumes of free gas can be handled than would be possible with containers exposed to the weather.

20 Another desirable feature of the holder above explained is that it lends itself easily to installation with both new and existing holders. The operation of the device is as follows: To admit gas from a generating 25 plant to the high pressure container, close valves 29 and 31 and open valves 28 and 30 until the desired amount of gas is accumulated within the high pressure container.

30 To admit gas from the gas plant to the low pressure container close the valves 28 and 31 and open the valves 29 and 30. In some instances the valve 31 may remain open under such circumstances.

35 To admit gas from the high pressure containers to the low pressure container merely close the valves 30 and 31 and open the valves 28 and 29 and in some instances the valve 31 may remain open when it is desired to supply gas to the distributing main 40 while supplying gas to the low pressure container.

I claim:

1. A gas holder having, in combination, a 45 low pressure gas container; a plurality of high pressure spherical gas containers within said low pressure container; means for supplying gas from said high pressure

containers to said low pressure container; and means for preventing the accumulation of water under said high pressure container 50 consisting of a water-tight connection between the outer portions of said high pressure containers and the floor of said low pressure container.

2. A gas holder, having in combination, 55 an outer low pressure gas holder; a plurality of high pressure spherical gas holders within said low pressure holder; means for supplying gas to said low pressure holder from said high pressure holder; means for 60 supplying gas to said high pressure holders; and means for preventing the accumulation of water under said high pressure containers.

3. A gas holder having, in combination, 65 a foundation; an outer low pressure gas holder comprising a tank having a plurality of lifts; a plurality of high pressure gas holders mounted on the foundation within said holder; a valve-controlled pipe between said high pressure shells and said low pressure holder; a high pressure delivery pipe 70 leading from said high pressure gas shells; a low pressure delivery pipe leading from said low pressure holder; and sealing means for preventing the accumulation of water 75 under said high pressure shells.

4. A gas holder having, in combination, 80 an outer low pressure gas holding container including a plurality of lifts for maintaining approximately uniform pressure therein; 85 a plurality of rounded high pressure gas containers within said low pressure container adapted to withstand submerged pressure obtainable within said low pressure container; valve controlled pipe means for connecting said high and low pressure containers; a valve controlled high pressure gas pipe for supplying said low pressure containers; a low pressure gas delivery pipe discharging from said low pressure container; and means for preventing the accumulation of water under said high pressure containers. 90

ARTHUR H. T. WILLIAMS.
